Specification for Design.

Patented Feb. 10, 1914.

Application filed December 3, 1913. Serial No. 804,512. Term of patent 14 years.

To all whom it may concern:

Be it known that I, HENRY H. BRAUTIGAM, a citizen of the United States, and resident of Bridgeport, county of Fairfield, Connecticut, have invented a new, original, and ornamental Design for Internal-Combustion-Engine Manifolds, of which the following is a specification, reference being had to the accompanying drawing, forming part hereof.

The figure is a perspective view of an in-

ternal combustion engine manifold, showing my new design.

I claim:

The ornamental design for an internal combustion engine manifold, substantially as shown.

HENRY H. BRAUTIGAM.
